By his atty.
UNITED STATES PATENT OFFICE.

HENRY O. SCHMIDT, OF NEW YORK, N. Y., ASSIGNOR TO SIMONS, BROTHERS & CO., OF PHILADELPHIA, PENNSYLVANIA.

DESIGN FOR A CANE OR UMBRELLA HANDLE.

SPECIFICATION forming part of Design No. 20,552, dated March 3, 1891.

Application filed February 6, 1891. Serial No. 380,611. Term of patent 3½ years.

To all whom it may concern:

Be it known that I, HENRY O. SCHMIDT, a citizen of the United States, residing in New York, in the county and State of New York, 5 have invented and produced a new and original Design for Cane or Umbrella Handles, of which the following is a specification, reference being had to the accompanying drawing, forming part thereof.

10 In the drawing is represented a side elevation of a cane or umbrella handle illustrating my new design.

The shank A extends upwardly with a slight reverse curve and terminates in the crook B. 15 The adjacent portions of the crook B and shank A are ornamented by scrolls D. The lower portion of the shank is ornamented with vertical ribs F, which pass upwardly and run

into the ridges between the grooves C, which ornament the crook B. The general surface 20 of the handle is smooth. The base of the shank A is ornamented by an annular band E of the configuration shown.

The handle is made of any suitable material. 25

Having now described my design, what I claim as new, and desire to secure by Letters Patent, is—

The design for cane or umbrella handles, substantially as herein described and shown. 30

In testimony of which invention I have hereunto set my hand.

HENRY O. SCHMIDT.
